Patented Sept. 11, 1973

228,368

WARNING LIGHT FOR SHOPLIFTERS IN STORES OR SIMILAR ARTICLE

Robert J. Slavsky, Lathrup Village, Mich., assignor to Shaw & Slavsky, Inc., Detroit, Mich.

Filed Oct. 12, 1971, Ser. No. 188,644

Term of patent 14 years

Int. Cl. D29—99

U.S. Cl. D72—1 E

FIG. 2

FIG. 3

FIG. 1 is an elevation view of a warning light for shoplifters in stores or similar article showing my new design the other sides being identical to the side shown;

FIG. 2 is a top plan view, and

FIG. 3 is a cross sectional view taken on line 3—3 in FIG. 1.

The indicia is shown in broken lines in FIG. 1 for illustrative purposes only.

I claim:

The ornamental design for a warning light for shoplifters in stores or similar article, substantially as shown and described.
